United States Patent Office.

NATHAN HUNT, OF SALEM, OHIO.

Letters Patent No. 68,989, dated September 17, 1867.

IMPROVEMENTS IN ENGINE-PISTONS.

The Schedule referred to in these Letters Patent and making part of the same.

TO ALL WHOM IT MAY CONCERN:

Be it known that I, NATHAN HUNT, of Salem, in the county of Columbiana, and State of Ohio, have invented a new and useful Improvement in Pistons; and I do hereby declare that the following is a full, clear, and exact description thereof, which will enable those skilled in the art to make and use the same, reference being had to the accompanying drawings, forming part of this specification.

This invention relates to a new and improved method of constructing the pistons of steam-engine cylinders, and it consists in making the piston self-packing by means of rings of peculiar construction, and which are expanded by the pressure of the steam, as will be hereinafter more fully described.

Figure 1 represents a vertical central section of the piston, it being through the line xx of fig. 2.

Figure 2 is a horizontal section of the same through the line yy of fig. 1.

Similar letters of reference indicate corresponding parts.

A is the piston-head, which is rigidly attached to the piston-rod. B is the piston-rod. C is the follower, which is slipped on to the lower end of the piston-rod, and fastened with a screw-nut, α , as seen. There are four packing-rings, two outside and two inside. The outside rings are marked D and the inside rings are marked E. The rings D are L-shaped; as seen in the drawing, and meet and form a joint in the centre of the piston, their outer surfaces forming the entire wearing surface against the cylinder. The inner surfaces (or short part of the L) enter the chamber or groove formed between the piston-head A and the follower C. The inside rings E are square in their cross-section, and occupy the interior portion of the chamber, being colored blue in the drawing. The piston-head A and the follower C are fitted and screwed together tightly, and the rings are fitted into the chamber, so that they are allowed to expand freely.

It will be noticed that the peripheries of the piston-head and the follower are bevelled, so as to leave an annular space, e , inside the rings D. The steam enters this annular space freely, and expands the rings on the upper and lower sides of the piston alternately, as it is moved up and down or back and forth in the cylinder. All the rings (D and E) in one or more places are cut, as seen in fig. 2, at ff , and the pieces are arranged to break joints. The annular steam space e is made of a depth to correspond with the diameter of the piston, or as experience might prove to be best. The advantages of this piston over those in ordinary use are many, and must be obvious to all who are acquainted with the subject.

What I claim as new, and desire to secure by Letters Patent, is—

The construction and arrangement of the L-shaped packing-rings D, whose inner projections rest against each other, and are inserted in the space between the piston-head A and follower C, holding the packing-rings E in position, said piston-head and follower provided with inclined recesses e upon their peripheries, to admit the steam behind the rings B and E alternately, at each upward and downward stroke of the piston, as herein shown and described.

NATHAN HUNT.
